CONVEYER FOR KILNS

Lester L. Ladd, Lockport, Ill.

Application January 15, 1934, Serial No. 706,607

3 Claims. (Cl. 25—142)

This invention relates to conveyers for kilns employed in firing or baking ceramic wares, a kiln of this general type being disclosed in my former Patent No. 1,842,411, dated January 26, 1932.

In the operation of these kilns, where the sectional table or platform directly supporting the wares is rigidly attached to a carriage structure carrying one or more rails which ride on a group of rollers, considerable difficulty has been experienced in the operation of the conveyer due to the contraction and expansion of the sectional table or platform relative to the underlying carriage, causing lateral straining and distortion of the connections.

The main object of the present invention is to provide an improved carriage structure and connections therefrom to the table or platform, whereby the above noted fault may be remedied, and the expanding and contracting movements of the platform or carriage are not transmitted to the carriage.

One practical form in which the invention may be embodied is illustrated in the accompanying drawings in which—

Fig. 1 is a vertical fragmentary section through the kiln and conveyer, taken on the line 1—1 of Fig. 3.

Fig. 2 is a sectional detail, illustrating a slideable connection between the brace or strut which supports the carriage or platform and one of the annular beams to the lower side of which is connected the rail that rides on the supporting and driving rollers.

Fig. 3 is a vertical section taken on the line 3—3 of Fig. 1.

Fig. 4 is a fragmentary plan view illustrating the sectional character of the ware-supporting platform or table.

Referring to the drawings, 10 designates the brick walls of the furnace which are built on a concrete base 11 formed of floor slabs which in turn are supported substantially at the ground level on plates 12 that, in turn, rest on angle bars 13. The angle bars 13 in turn are riveted to the upper ends of posts 14, and similarly riveted to the lower ends of the posts 14 are angle bars 15 that rest on a concrete foundation 16 and thus spread the load over a large area of concrete.

The walls 10 form between them the annular channel or trough through which the conveyer travels. The plates 12 are extended inwardly to support shields 17 that, with the opposed vertical walls of the slabs 11 form channels 18 which are filled with sand or other suitable sealing material to prevent the heat in the upper

part of the trough from reaching the underlying pit 19, in which the bearings and driving mechanism are located.

Describing now the sectional annular conveyer on which the wares are deposited prior to their travel through the kiln, 20 designates each of a group of sectional cast iron plates cast with upturned flanges 21 on their ends and seating a heat insulation block 22. Resting on the block 22 is the thick refractory slab 23 which directly supports the wares to be heat treated. To the flanges 21 of the plate 20 are secured depending aprons 24 which dip into the body of sand in the troughs 18 and thus complete the heat seal.

25 designates each of a pair of annular I-beams underlying the sectional plates 20, to the lower end of which are secured by clips 26 and cleats 27 a pair of annular rails 28 that rest and ride on the rollers 29 mounted on shafts 30.

The tables or plates 20 are supported on the beams 25 by inwardly inclined struts 31, these latter being bolted to lugs 32 on the under side of the plate 20 and at their lower ends formed with eyes or holes 33 that, as best shown in Fig. 2, loosely encircle collars 34 mounted on bolts 35 extending through the lower portions of the beams 25 and secured against escape by nuts 36 and washers 37.

By reference to Fig. 2 it will be observed that the collars 34 are considerably wider than the lower portions of the struts 31 which encircle them, so that the struts 31 may have a considerable inward and outward movement on the collars 34, resulting from expansion and contraction of the plates 20 without imposing any lateral strain on the beams 25.

Referring to the cleats 27 on which the I-beams 25 rest and to the under side of which the rails 28 are secured, about every fourth one of the cleats 27 is made of sufficient length to span the distance between the two rails 28, as indicated in Fig. 1, so as to tie the rails in parallel relation.

The shafts 30 carrying the rollers 29 are journaled in bearings 38 (Fig. 3) formed as parts of yokes 39, the ends of which rest on shouldered collars 40 that are threaded on screws 41 and locked in vertically adjusted position by upper and lower nuts 42 and 43. The lower ends of the screws 41 are footed in seats 44 formed integral with a base casting 45 that, in turn, rests upon and is bolted to the angle bars 15. Manifestly, by adjusting the collars 40 up or down, the shaft 30 and its rollers 29 can be so adjusted throughout the entire series of roller supports as to properly engage with and support the rails 55

28 and maintain the conveyer perfectly level. In practice, two diametrically opposed shafts 30 will constitute drive shafts which are driven by suitable motors in the manner indicated in Fig. 5 5 of my former patent above referred to.

As shown in Fig. 1, one of the rollers 29 is flanged so as to prevent any danger of the rails 28 accidentally riding off their supporting and driving rollers.

10 The improvement as herein shown is preferably a double rail system, employing two annular beams 25 rigidly connected and spaced at their bottoms and two rails 28 riding on a pair of rollers 29; but, so far as the feature of providing lost motion or play in a sidewise direction 15 between the supporting struts or brackets 31 and the beams 25 to compensate for expansion and contraction of the plates 20 is concerned, a monorail system, such as is shown in my Patent 20 1,842,411 might be employed, with the inclined struts or brackets 31 engaging opposite sides thereof.

The parts are shown in Fig. 1 in the relative 25 positions they assume when the parts are cold. In firing or baking ceramic ware in these kilns very high temperatures are employed, which give an appreciable expansion of the sectional cast iron plates 20; and as this expansion occurs, the supporting brackets or struts 31 can, manifestly, 30 slide bodily outwardly on their supporting collars 34 without creating any bending strain on the brackets or any lateral strain on the annular beams 25.

The structural details may be more or less 35 varied without departing from the substance of the invention or sacrificing any of its advantages, and hence I reserve all such variations

and modifications as fall within the spirit and purview of the appended claims.

I claim:

1. A conveyer for kilns, comprising a table movable along a horizontal path, rollers journaled beneath said table, a carriage including twin rails supported on said rollers and twin annular beams mounted on said rails, and depending struts on the under side of said table supported on said beams with capacity of limited 10 lateral shift relatively to said beams under expanding and contracting movements of said table.

2. A conveyer for kilns, comprising a table movable along a horizontal path, rollers journaled beneath said table, a carriage including 15 twin rails supported on said rollers and twin beams mounted on said rails, depending struts on the under side of said table formed with holes in their lower ends, and laterally projecting supports on the sides of said beams extending 20 through the holes of said struts and of greater length than the thickness of the engaging portions of said struts.

3. A conveyer for kilns, comprising a table movable along a horizontal path, rollers journaled beneath said table, a carriage including twin rails supported on said rollers and twin beams mounted on said rails, tie-bars connecting and spacing said rails and beams, inwardly inclined depending struts on the under side of said 30 table formed with holes in their lower ends, and laterally projecting supports on the sides of said beams extending through the holes of said struts and of greater length than the thickness of the 35 engaging portions of said struts.

LESTER L. LADD.
